PORTABLE DISPLAY

Belmont Corn, Jr., Scarsdale, N. Y., and Charles D. Roscher, Bogota, N. J., assignors to The Displayers, Inc.

Application January 17, 1951, Serial No. 206,492

2 Claims. (Cl. 160—135)

1

This invention relates to display apparatus and more particularly to a display which may be knocked down or collapsed for packaging in a relatively light, easy-to-handle packing case.

The new apparatus comprises a plurality of demountable support panels capable of being assembled together to form a display screen in a variety of specific arrangements. Each panel is made up of four lightweight tubular frame members made preferably of a hard aluminum alloy. Two of the tubular members are substantially U-shaped while the remaining two are straight and are adapted to interconnect the arms of the two U-shaped members. The connection between a straight member and the arm of a U-shaped member is preferably of the telescopic type, the end of one having a portion of substantially reduced diameter and being adapted to receive over this portion the end of the other. A thumb screw is also provided at each connection of a straight member with the arm of a U-shaped member to press the telescoping portions of the interconnection into tight frictional engagement with each other whereby the two members may be locked together. The support panels which may all be of the same size or, as will be subsequently described in connection with a preferred embodiment of the invention, may be of different sizes, are adapted to be hinged together by clamps which permit adjustable, angular relative positioning of the panels with respect to one another.

A plurality of reticulated display panels, preferably made of expanded aluminum sheet, are provided and may be detachably secured to the support panels in the planes thereof and between the tubular frame members. These display panels are adapted to support, in various positions and arrangements, plaques containing advertising copy, photographs, charts and the like. If desired the display panels may be made of materials other than expanded aluminum sheet. For instance, perforated Masonite lacquered in any color may be used instead.

To fill out the support panels and to provide a proper and pleasantly appearing background for the advertising copy supported on the reticulated display panels, a curtain is provided for each panel and is adapted to be removably or detachably secured thereto, for instance by snap grippers. These curtains are sufficiently large to completely fill the open spaces between the frame members of the support panels to which they are to be attached. The curtains may be made of any number of materials such as cloth fabric, woven wood screen, Leatherette or natural-grain

2

Flexwood and may be of a variety of colors. However in the preferred form of apparatus they are made of differently colored fabrics.

Also provided in the display apparatus are a number of shelves which may be detachably secured to the frame members of the support panels. These shelves are intended to support various articles being displayed.

A packing case, preferably of lightweight plywood, is included and is of a size sufficient to contain our entire display apparatus in knocked-down or collapsed condition. The packing case however performs another function and that is to support a collapsible counter surface. A drape or cover, preferably of the same material as the curtains for the support panels, is provided to cover the counter supported by the packing case and to extend to the floor thereby hiding from view the open packing case and resulting in the composite counter appearing to be a table.

Lastly a number of electric lamps, provided preferably with spun aluminum shades, are included for lighting the exhibit. These lamps are provided with pipe clamps operable by a single thumb screw for attachment to a tubular frame member of the support panels.

For a more detailed description of the preferred embodiment of our invention reference may be made to the accompanying drawings in which, Fig. 1 is a perspective view of the apparatus set up for display purposes;

Fig. 2 is a perspective view of the packing case containing the entire display apparatus in knocked-down form,

Fig. 3 is a perspective view of the counter-table, and

Fig. 4 is a diagrammatic representation of an arrangement of the support panels different from that shown in Fig. 1.

By reference first to Figs. 1 and 2 the portable display apparatus will be seen to comprise a plurality of similar support panels. Broad panels 10, 11 and 12 in the specific screen shown, are of one size and narrow panels 13 and 14 of another size. Each of support panels 10—12 comprises a pair of broad U-shaped tubular frame members 15 and a pair of straight tubular frame members 16, the individual frame members being best seen in Fig. 2. Straight frame members 16 are provided at their opposite ends with portions 17 of reduced diameter these portions being provided with slots 18 and thumb screws 19 whereby they are expandable. The hollow ends of the U-shaped frame members 15 are adapted 55 to fit over the reduced end portions 17 of the

straight members 16 and are provided with slots 20 to receive the shanks of thumb screws 19. When the ends of members 15 are telescoped over the reduced end portions 17 of straight members 16 the thumb screws may be turned thereby expanding the reduced end portions 17 resulting in tight frictional locking of the telescoped portions of the frame members.

Support panels 13 and 14 comprise a pair of straight members 16 and a pair of narrow 10 U-shaped members 21. The ends of the arms of U-shaped members 21 are slotted similarly to the ends of frame members 15 and the connections between these U-shaped members and the straight members to form panels 13 and 14 are 15 the same as are those of broad panels 10-12.

The various support panels 10-14 may be hinged together in a variety of different ways by a number of clamps 22. For instance, as illustrated in Fig. 1 the three broad support panels 20 10-12 may be adjacent one another with the narrow support panels 13 and 14 being disposed outwardly therefrom. Or as illustrated in Fig. 4, the smaller support panels 13 and 14 may separate the larger support panels 10-12 from one another. It will be clear of course that the angular relationship of the support panels with respect to one another may also be varied at will. A number of reticulated display panels 23, each comprising an aluminum frame 24 supporting a 30 piece of expanded aluminum sheet 25, are provided and are adapted to be detachably secured in any detachable manner to the frame members of the support panels. These reticulated display panels 23 may be employed to support in various arrangements plaques containing advertising copy, photographs, charts, or the like.

A number of shelves 26 are provided to be detachably secured across the various support panels and may be used for supporting articles which are to be displayed.

Each of the panels 10-14 is additionally provided with a curtain 27 made as has been previously stated, of cloth fabric, Leatherette, etc., which may be fastened, as by snap grippers (not 45 shown), to the panel to form a pleasingly appearing background for the material to be exhibited. As will be seen in the drawings, curtains 27 are sufficiently large to completely fill the open spaces between the frame members of 50 the support panels.

A pair of lightweight electric lamps 28 having spun aluminum shades may be secured by clamps 29, with which they are provided, to any portion of any of the frame members of the support 55 panels for the purpose of lighting the display. In most cases two lamps are sufficient for this purpose but of course a greater number may be employed.

A packing case 30 of ply-wood is fitted to receive the knocked-down apparatus as shown in Fig. 2. As may be seen in Fig. 3, case 30 is intended also to be used as a support for a folding counter board 31. A drape cover 32, made preferably of the same material as are the curtains 27, fits over counter board 31, and hangs to the floor thereby hiding the packing case from view and giving the composite counter the appearance of a table as indicated in Fig. 1. It will be seen from Fig. 2 that the interior of the 70 packing case 30 is provided with a variety of

parts and guides for receiving and maintaining the various knocked-down parts of the display apparatus tightly packed therein.

The desirable attributes of our portable display apparatus are many, but among the most important are its characteristic of providing a large display area when assembled yet requiring a very small space when knocked-down and packaged. It furthermore is very light in weight, the entire apparatus weighing less than 100 lbs. and therefore may be easily and readily handled. Additionally, a large degree of flexibility in appearance is achieved by reason of the various arrangements of the support panels, the display panels, and the curtains which its novel construction permits to be employed. For example, instead of assembling the display screen as a whole by locating the two narrow support panels 13 and 14 on the outside, as shown in Fig. 1, the latter may form interior support panels, as shown in Fig. 4, without making any change in the sub-assemblies of paired straight tubular members 16 and clamps 22 as they are taken from case 30 (Fig. 2).

It will also be apparent that various changes and modifications may be made in the apparatus without departing from our invention the scope of which should not be limited except to the extent set forth in the appended claims.

We claim:

1. Portable display apparatus comprising a plurality of support panels hinged to one another, each of said support panels comprising a pair of substantially U-shaped tubular members and a pair of straight tubular members demountably interconnecting the arms of one U-shaped member to the arms of the other U-shaped member, a plurality of display panels detachably secured to members of the support panels and supported substantially in the planes of the support panels, and a plurality of curtains detachably secured to the members of the support panels, each of said curtains occupying the major portion of the space between the tubular members of the associated support panel.

2. Portable display apparatus according to claim 1 in which each arm of a U-shaped tubular member is connected to a straight tubular member by a telescopic connection, the end of one being of reduced diameter to receive over it the end of the other, and each connection including a thumb screw for pressing the telescoping portions into tight frictional engagement with each other.

BELMONT CORN, JR.
CHARLES D. ROSCHER.
